Attorney.

UNITED STATES PATENT OFFICE

111,227

DESIGN FOR AN ASHTRAY

Martin Secan, Highland Park, Mich.

Application March 25, 1938, Serial No. 76,099

Term of patent 7 years

To all whom it may concern:

Be it known that I, Martin Secan, a citizen of Yugoslavia, residing at Highland Park, in the county of Wayne and State of Michigan, United States of America, have invented a new, original, and ornamental Design for an Ashtray, of which the following is a specification, reference being had to the accompanying drawing, forming a part of the disclosure herewith.

With reference to the drawing:

Figure 1 is a perspective view of the ashtray showing my new design, Figure 2 is an elevational view partially in section, taken through the diametrical center thereof, to more clearly illustrate

the integral formation of the cigar or cigarette holder or rest and the bottom of the ashtray.

The characteristic features of my design reside in an ashtray having a polygonal shaped wall, substantially as shown, a polygonal shaped overhanging bead at the upper edge of the polygonal wall forming the rim thereof, the interior of the ashtray sloping inwardly from the rim to the center.

I claim:

The ornamental design for an ashtray, substantially as shown and described.

MARTIN SECAN.
